SAFETY CATCH FOR PIN STEMS

Anthony C. E. Waller, Edgewood, R. I.

Application March 21, 1933, Serial No. 661,866

10 Claims. (Cl. 24—157)

This invention relates to a safety catch for pin stems and the like and has for one of its objects the provision of a complete catch and in addition a locking gate therefor which will be securely held across the entering opening for the pin stem to prevent accidental detachment of the pin stem from the catch.

Another object of the invention is the provision of a safety catch which may be made inexpensively and of a minimum number of parts and cut out in multiple and assembled by machine tool operation thus reducing expense of construction.

Another object of the invention is the provision of a construction in which the pin stem will assist in maintaining the gate in closed position.

Another object of the invention is the location of the gates that the base may be engaged to drive the points thereof into the ornament.

Another object of the invention is the provision of a construction in which the pivot point about which the gate will rock may be formed integral with one of the ears and positioned in an opening in the gate by a folding operation.

A further object of the invention is the provision of a finger piece which, in addition to its function of serving to manipulate the swingable gate, also serves as a stop to limit the opening movement of the gate that it may always be in a position for convenient operation by the user.

With these and other objects in view, the invention consists of certain novel features of construction, as will be more fully described, and particularly pointed out in the appended claims.

In the accompanying drawing:

Fig. 1 is a perspective view of the back of an ornament showing a pin stem and safety catch as provided thereon.

Fig. 2 is a perspective view of the safety catch as cut out from sheet stock.

Fig. 3 illustrates the safety catch as partially folded into finished position.

Fig. 4 is a perspective view of the gate.

Fig. 5 is a central sectional view showing the gate in closed position.

Fig. 6 is a central sectional view showing the gate in open position.

Fig. 7 is a sectional view on line 7—7 of Fig. 5.

Fig. 8 is a view similar to Fig. 5 showing a modified form of gate.

In the use of safety catches on bar pins, ornaments, badges and the like, it is necessary to provide a catch which will secure the pin stem in position and in addition to such a catch it is desirable to provide a locking device which

will prevent the pin stem from being accidentally removed from the catch, and in order that this may be obtained in a simple, efficient manner and one which may operate conveniently and easily I have cut out a catch from sheet stock ⁶⁰ and provided the same so that it will function regardless of a gate or locking device, and then have additionally provided a gate or locking device to cooperate with the catch and prevent accidental disengagement therefrom, and I have so arranged by integral pivot and recess openings that the parts may be assembled by merely folding the catch into its finished position with the gate so located that the catch may be driven into an ornament if desired, and the following ⁷⁰ is a detailed description of the present embodiment of this invention illustrating the preferred means by which these advantageous results may be accomplished.

With reference to the drawing, 10 designates ⁷⁵ a bar pin or ornament which is provided with a hinge joint 11 pivotally mounting a pin stem 12 which swings about the pivot 13 and engages the stop 14 that tension may be applied on the pin stem engaging with the catch. The catch is ⁸⁰ shown blanked out in Fig. 2 which consists of a flat piece of stock 15 cut out in the shape there shown with an integral portion 16 forming a pivot pin raised from the stock thereof. This blanked out form is folded as at 17 and 18 providing a ⁸⁵ base 19 with ears 20 extending upwardly from either side of this base and attaching prongs 30 folded downwardly from the ends of the base. These ears are each hook shaped providing a shank portion 21 and an opening 22 into which ⁹⁰ the pin stem 12 may be positioned and by reason of its resiliency will move to engage upper portion 23 of the arc of the hook to retain the same in position. These hooks are on substantially the arc of a circle or generally of this shape for ⁹⁵ convenience of operation as will more fully hereinafter appear.

Between the hook ears 20 and 21 I have mounted a gate 25 which is a shape shown in Fig. 4 being generally arcuate and generally conforming to the shape of the hook. This gate is provided with an ear 26 having a pierced opening 27 which receives the integral pin 16 to pivotally mount this gate between the ears 20. Pivot 16 is located along the shank portion 21 of the hook so that the gate when moved to closed position substantially conforms to the shape of the hook and extends across the opening 22 thereto to prevent the exit of the pin stem 12 for detachment from ¹⁰⁰ the catch. ¹⁰⁵ ¹¹⁰

In order that this gate may be easily manipulated I have provided a finger piece 28 which is so located that it will engage the base 19 as will be apparent from Fig. 6 to limit the opening of the gate from its locking position. This limiting will be in such a position that the gate 25 may be readily engaged for closing the gate or moving it to the position such as shown in Fig. 5 with its end portion 29 across the opening 22.

10 In order to better retain the gate in position there may be provided, as in the modified showing in Fig. 8, a projection 31 which will be forced past the resilient pin stem and with which the pin stem engages should the gate tend to accidentally open, there being required considerable pressure to open the gate by reason of this locking projection. Thus an additional safety feature in the catch is provided which is desirable to prevent loss of a bar pin ornament or the like 15 in connection with which the same is used.

20 The prongs 30 of the base which I have provided affording convenient attachment to a celluloid object into which they may be driven, or a flat base without these prongs may be used, by 25 soldering some other attachment to a metal base. It is, however, a feature of this construction that the gate swings out from across the base so that the base may be engaged by a tool to drive the prongs into a celluloid or like mounting for the 30 catch.

35 The foregoing description is directed solely towards the construction illustrated, but I desire it to be understood that I reserve the privilege of resorting to all the mechanical changes to 35 which the device is susceptible, the invention being defined and limited only by the terms of the appended claims.

I claim:

40 1. A safety catch comprising a member having a base attachable to a suitable support and a pin stem catch secured to said base consisting of a generally hook shaped portion, and a gate pivotally mounted on the back of said catch and swingable across the opening to said hook to prevent the exit of a pin stem from said catch.

45 2. A safety catch comprising a member having a base attachable to a suitable support and a pin stem catch secured to said base consisting of a generally hook shaped portion on generally the 50 arc of a circle and a gate pivotally mounted on the back of said catch and swingable across the opening to said hook to prevent the exit of a pin stem from catch, said gate being generally arc shaped and generally following in its movement 55 the arc of said catch to close the opening to said catch.

60 3. A safety catch comprising a member having a base attachable to a suitable support and a pin stem catch secured to said base consisting of a generally hook shaped portion on generally the 65 arc of a circle and a gate pivotally mounted on the back of said catch and swingable across the opening to said hook to prevent the exit of a pin stem from catch, said gate being generally arc shaped and generally following in its movement the arc of said catch to close the opening to said catch, and means on said gate to co-act with the pin stem to prevent the gate from moving to open 70 position.

70 4. A safety catch comprising a member having a base attachable to a suitable support, said base

being provided at either side with spaced ears integral with said base and of a hook shape providing a catch for a pin stem, and a gate pivotally mounted between said ears at a point along the shank of one of the hooks and swingable across the opening of said hooks of said catch to prevent detachment of a pin stem from said catch. 80

5. A safety catch comprising a member having a base attachable to a suitable support, said base being provided at either side with spaced ears integral with said base and of a hook shape and on generally the arc of a circle providing a catch for a pin stem, and a gate pivotally mounted between said ears at a point along the shank of one of the hooks and swingable across the opening of said hooks of said catch to prevent detachment of a pin stem from said catch, said gate being generally arc shaped and generally following in its movement the arc of said catch to close the opening to said catch. 85

6. A safety catch comprising a member having a base attachable to a suitable support, said base being provided at either side with spaced ears integral with said base and of a hook shape and on generally the arc of a circle providing a catch for a pin stem, and a gate pivotally mounted between said ears at a point along the shank of one of the hooks and swingable across the opening of said hooks of said catch to prevent detachment of a pin stem from said catch, and means on said gate to 100 co-act with the pin stem to prevent the gate from moving to open position. 95

7. A safety catch comprising a member having a base attachable to a suitable support, said base being provided at either side with spaced ears integral with said base and of a hook shape providing a catch for a pin stem, one of said hooks having an integral pivot raised from the stock thereof along its shank and extending toward the other hook, a gate having an opening therein receiving 110 said pivot to swingably mount the gate between the ears, said gate being movable across the opening to said hooks of said catch to prevent the detachment of a pin stem therefrom. 115

8. A safety catch comprising a member having a base attachable to a suitable support and a pin stem catch secured to said base consisting of a generally hook shaped portion, and a gate pivotally mounted on the back of said catch and swingable across the opening to said hook to prevent the exit of a pin stem from said catch and a finger piece on said gate located to engage said base and limit the opening movement of said gate. 125

9. A safety catch comprising a member having a base, prongs on the base, a pin stem catch on 130 said base having an opening to receive a pin stem and a gate to close the opening to said catch, said gate being so shaped and pivotally mounted on said member at a location so that the gate may be moved to a position out of the way when driving 135 the member into a suitable support.

10. A safety catch comprising a member having a base, prongs on the base, a pin stem catch on 140 said base having an opening to receive a pin stem and a gate to close the opening to said catch, said gate being so shaped and pivotally mounted on said member at a location that it will swing clear of the upper surface of the base to permit insertion of a tool for driving the base into a suitable support. 145
